UNITED STATES PATENT OFFICE.

JAMES CRETE HUBBARD AND ALBERT F. WINN OF ELDORADO, KANSAS; SAID WINN
ASSIGNOR TO SAID HUBBARD.

CARD OR PLACARD HOLDER.

Application filed August 11, 1922. Serial No. 581,159.

To all whom it may concern:

Be it known that we, JAMES CRETE HUBBARD and ALBERT F. WINN, citizens of the United States, and residents of Eldorado, in the county of Butler and State of Kansas, have invented certain new and useful Improvements in Card or Placard Holders, of which the following is a specification.

This invention relates to card or placard holders and particularly to devices of this type adapted to be attached to tank cars or other containers of inflammables to removably secure the cards or placards thereto upon which may be displayed the required 10 warning that the contents of the car is inflammable.

Heretofore paper or cardboard cards have been employed but these have been found objectionable because they were easily destroyed by the elements such as wind and rain. Therefore cars which were dispatched properly placarded as required by the regulations of the Bureau of Explosives have at 20 their destination been found to be minus these required placards because during transit the same have been destroyed in the manner above mentioned.

It is therefore the object of this invention to provide a metallic card or placard and a holder whereby the same may be removably secured in place. On one face of the placard will be stenciled the "inflammable" sign and on the reverse side the name of the owner or lessee and home port so that 30 when there is no need for the placard under the Bureau of Explosives regulations the placard may be reversed to indicate the name of the owner or operator and the home port of the car. Of course even when the placard is reversed the other side of the placard is visible from certain angles.

The advantages and features of this present invention will be made more apparent as the description proceeds and particularly 40 in view of the accompanying drawings wherein:

Fig. 1 is a fragmentary perspective view of a tank car with the placard and placard holder in place,

Fig. 2 is a side elevation partly in section of the device,

Fig. 3 is a top plan view,

Fig. 4 is a fragmentary section taken on the plane indicated by line 4—4 in Fig. 2,

Fig. 5 is a fragmentary section taken on the plane indicated by line 5—5 in Fig. 2, and

Fig. 6 is a fragmentary perspective view of a modification.

Referring more particularly to the drawings wherein like reference characters indicate like parts it will be seen that there is illustrated a portion of a tank car 10 provided with a running-board 11. In practice it will be desirable although not necessary to provide four of the holders and cards to a tank car, the holders being bolted from the bottom of the running-board adjacent the inner edge thereof as clearly illustrated, one holder being arranged at each end of the 60 car and at each side.

The holder comprises a casting 12 provided with a base 13 formed by bending the body of the holder at right angles. Bolts 14 passing upwardly through apertures 14^a 75 formed in the base 13, pass through the running board 11 and nuts 15 are employed for rigidly holding the holder in place.

The holder is formed of metal and may be cast or may be formed of sheet metal 80 properly shaped. In either event there is provided an angular groove or recess 16 composed of two right angular portions and adapted to receive two sides of a metal placard or card 17. The recess or groove 16 85 is formed by providing a pair of spaced flanges 18, U-shaped in cross section and spaced a sufficient distance to loosely receive the edge of the placard or card 17. One end of this groove is closed by a lip 19 90 while the other end is open as at 20, see particularly Figs. 2, 4 and 5.

The placard 17 is formed with angular extensions or corners 21 which are adapted to lie in the closed end 19 and the open end 95 20 of the placard receiving recess. Obviously in inserting the placard in place the one corner 21 is inserted in the closed end 19 of the recess and the other end then brought into the position illustrated in Fig. 2. Each end of the card or placard is apertured as indicated at 22 which apertures coincide in either position of the placard with the pair of openings 23 provided in the slotted end 20 of the holder whereby a cotter pin 100 24 or the like may be inserted through the aligned openings to secure the placard 17 in place. Obviously by reversing the placard 105

the other opening 22 may be caused to register with the apertures 23 to accommodate the cotter pin 24.

In some instances it may be desirable to 5 secure the placard to the holder 12 by means of a seal 25 (see Fig. 6). In this instance the end of the placard 17 is slotted in the open end 20 of the holder whereby the strap of the seal 25 may be passed therethrough.

10 The manner of using this improved placard and placard holder will be immediately apparent. With the holder or frame 12 secured to the running-board 11 the placard 17 bearing on one side thereof the notice of 15 the inflammability of the contents of the car and on the other side the name of the owner or lessee and home port is inserted in the first instance with the word "Inflammable" outward. In inserting the placard 17 the 20 one angular corner 21 thereof is inserted in the closed end 19 of the holder and the placard 17 seated in the recess or groove 16 formed in the holder 12. As the placard 17 is seated the other angular end 21 which is 25 provided with either apertures 22 or a slot registers with the correspondingly shaped opening in the open end 20 of the holder. The placard is then locked to the holder either by the cotter pin 24 or the seal 25.

30 In instances where the bureau regulations do not require the placarding of cars the placard is removed and reversed so as to display the other side thereof upon which is delineated the name of the owner and of 35 the home port. The placard is then secured in place in a like manner.

Obviously the number of holders and placards may be varied as may their position 40 upon the car. Obviously they may be secured to the car in any position as in either event the placard 17 will be locked to the holder to eliminate the possibility of the same becoming lost. It will be furthermore obvious that by reason of the engagement of 45 the placard by the holder throughout two of its edges that the placard will be reinforced and prevented to some extent at least from becoming mutilated or being otherwise rendered unfit for use. Obviously a metal 50 placard is inherently more durable than the paper or cardboard placard now universally in use and the chances of loss of the placards by reason of the inclemency of the weather is practically eliminated.

55 While the physical embodiment of the invention described and illustrated herein is found to be satisfactory and efficient in every respect it is not intended that this invention be unnecessarily limited but reservation is hereby made to make such changes in the

details of construction as may come within the purview of the accompanying claims.

Having thus described the invention, what we claim is:

1. In a device of the class described a 65 holder having a recess formed with a locking portion, a reversible placard provided with locking portions and adapted to engage said recess with one of said locking portions in engagement with the locking portion of said recess and further means co-operating with said engaging locking portions for securing said placard to said holder.

2. In a placard holder for tank cars and 75 the like, a frame provided with an angular slot closed at one end and open at the other, a placard adapted to rest in said recess, said placard being provided with angular ends, 80 the closed end of said recess engaging one of said angular ends and means for securing the other angular end in the open end of said recess.

3. An arrangement of the class described 85 comprising a metal frame adapted to be secured to the running-board of a container of inflammables or the like, where this warning may be required, said frame being provided with an angular slotted portion, said slotted portion being closed at one end and open at 90 the other, a metal placard provided with angular extensions on two of its corners, said placard being adapted to rest in the said slot with one end thereof disposed under the closed end of said slot and means passing through the other angular end for securing the placard in place in said slot.

4. A card holder for tank cars comprising 100 a frame adapted to be bolted to the running-board of the tank car or otherwise applied to other cars, said frame being provided with a right angular slotted portion, a lip closing said slotted portion at one end, the other end of the slotted portion being open, a reversible metal placard provided with 105 angular extensions at two of its corners, one of said extensions being adapted to engage the under side of said lip and the other angular extension to lie in the open end of said slotted portion, registering openings in 110 the open end of said slotted portion, said placard being provided with an aperture in each of said angular extensions adapted in either positions to register with the openings formed in said slotted portions and a fastening member passing through said aligned openings for securing said placard to said holder.

JAMES CRETÉ HUBBARD,
ALBERT F. WINN.
